UNITED STATES PATENT OFFICE

2,599,190

FOUR-IN-HAND NECKTIE KNOT ANCHORS

Irwin McNiece, Los Angeles, Calif.

Application August 15, 1949, Serial No. 110,324

1 Claim. (Cl. 2—148)

1

My invention relates to neck ties, particularly of the four-in-hand type and has for its principal object, to provide simple and efficient means located on the rear face of the tie for engaging and holding the knot in proper position, after same has been tied and positioned to the satisfaction of the wearer.

A further object of my invention is, to provide a necktie knot anchoring device of the character referred to, which may be readily applied to the tie, which is entirely concealed when the tie is knotted and being worn and which is readily adjustable for a considerable distance on the tie, so as to engage the knot regardless of its location on the knot forming portion of said tie.

With the foregoing and other objects in view, my invention consists in certain novel features of construction and arrangement of parts which will be hereinafter more fully described and claimed and illustrated in the accompanying drawing, in which:

Fig. 1 is a perspective view of a conventional four-in-hand tie and showing my improved knot anchor positioned thereupon.

Fig. 2 is a rear elevational view of the knotted portion of the tie and showing the anchor engaged against the lower end of the knot.

Fig. 3 is a side elevation showing the anchor mounted on the hook engaging member of a conventional slide fastening device.

Fig. 4 is a front elevation of the anchor applied to the slide fastener hook engaging member.

Referring by numerals to the accompanying drawing, which illustrates a preferred embodiment of my invention, 10 designates a conventional four-in-hand necktie having the usual wide end front portion 11 and narrower end rear portion 12.

To provide a sliding base for my improved knot anchor or stop, the fabric strip 13, which carry the inter-engaging hooks 14 of a conventional slide fastener now widely used for closing openings in garments and the like, are secured by stitching or otherwise, on the rear face of that portion of the tie member 12 which passes through the knotted portion of member 11. These hook bearing strips 13 may have a length of from five to eight inches, more or less. The hooks 14 are closed or engaged and released by a sliding hook 15, actuated by a pivoted depending tab 16 and the knot engaging stop and anchor 17, in accordance with my invention, is suitably secured on the upper front face of said hook 15.

As seen in Figs. 3 and 4, the knot engaging member 17 may be in the form of a cross bar or

2

plate of sufficient size to provide a protuberance which projects outwardly and laterally from hook 15, to engage beneath the lower end of the rear portion of knot K and thus effectually prevent upward slippage of the narrower rear portion 12 of the tie through the knot, also, downward slippage of the knot on said narrower rear portion.

Before knotting the tie, sliding hook 15 is positioned at the lower ends of the hook carrying 10 strips 13 as seen in Fig. 1, with hooks 14 disengaged, and after the tie has been knotted and the knot properly positioned to the satisfaction of the wearer, beneath the front ends of the collar, slide 15, by means of tab 16 is moved upward 15 to engage hooks 14 of the fastener and position member 17 against the lower end of knot K, as seen in Fig. 2, thus providing the desired knot anchorage.

It is to be understood that, the frictional engagement of sliding member 15 with the inter-engaging hooks 14 and the underlying surfaces of the tapes or strips 13 which carry said hooks, is such as to hold said member in differently adjusted positions against certain slight or minimum degrees of pulling strains. Under such conditions and where member 15 is not provided with any projecting portions such as 17, for engaging beneath the lower rear end of the tie knot K, it is possible under light pulling strains incident to normal wear, and particularly where the tie is 25 made from smooth silk or satin, for the knot to slip down over member 15 and adjacent portions of the narrow depending tie end 12, but where said member is provided with a knot engaging member such as 17, somewhat larger than member 15, this downward slippage of the knot is prevented.

The size of the members 15 and 16 in the smaller sizes of slide fasteners now on the market 30 are not such as to effectually prevent sliding movement of the knotted portion of a four-in-hand tie on the narrow portion of the tie which passes through the knot.

Four-in-hand neckties now on the market are, 45 to a large extent, produced from silk, satin, rayon and other smooth finished slippery fabric and my improved knot anchoring device is particularly effective in firmly holding the knotted portions of such ties in proper position in the collar front opening after having been neatly and attractively tied.

The knot anchoring device herein disclosed, while particularly designed for use on four-in-hand neckties, may also be advantageously employed 50 on various articles of feminine wear, for

instance, belts, collars, neck pieces and the like, where one part is knotted for reception of another part of the same article.

Thus, it will be seen that I have provided a four-in-hand necktie knot anchoring device, that is simple in structure, inexpensive of manufacture and very effective in performing the functions for which it is intended.

I claim as my invention:

The combination with a one piece four-in-hand necktie having a front portion, in the upper portion of which is formed a knot, and a rear portion adapted to slide through said knot, of a flexible slide fastener member mounted on the rear outer face of that portion of the tie which slides 15 through the knotted portion, a substantial distance from the end thereof, a member mounted for longitudinal sliding movement upon said flexible fastener member, which member when moved upward, is positioned beneath the knot formed 20 in the front portion of said tie, a short transverse member on said sliding member, knot engaging

protuberances projecting outwardly from the ends of said sliding member and a pull tab pivoted to said sliding member.

IRWIN McNIECE.
